UNITED STATES PATENT OFFICE.

HARVEY W. MORLEY, OF ANGOLA, INDIANA, ASSIGNOR OF ONE-HALF TO WILLIAM H. WALLER, OF ANGOLA, INDIANA.

PAPER HOLDING AND FEEDING MEANS FOR DUPLICATING DEVICES.

1,188,976.

Specification of Letters Patent. Patented June 27, 1916.

Original application filed May 8, 1914, Serial No. 837,185. Divided and this application filed February 19, 1915. Serial No. 9,298.

To all whom it may concern:

- Be it known that I, HARVEY W. MORLEY, a citizen of the United States, and a resident of Angola, in the county of Steuben and 5 State of Indiana, have made certain new and useful Improvements in Paper Holding and Feeding Means for Duplicating Devices, of which the following is a specification.
- 10 My invention relates to improvements in paper holding and feeding means for duplicating devices, and it consists in the combinations, constructions, and arrangements herein described and claimed.
- 15 An object of my invention is to provide a device for duplicating the work done on a typewriting machine, in which paper holders are provided which dispense with the necessity of using carbon copies, thereby 20 eliminating the time necessary in inserting and taking out carbon paper, eliminating the cost of the carbon paper and doing away with the possibility of soiling hands of the operator by the handling of the carbon paper.

- 25 A further object of my invention is to provide a paper holder having guide means which enables the operator to tear off sheets of predetermined size.
- 30 A further object of my invention is to provide paper feeding and holding means whereby continuous rolls may be used both on the master typewriter and on the duplicator.
- 35 Other objects and advantages will appear in the following specification and the novel features of the device will be particularly pointed out in the appended claims.

40 My invention is illustrated in the accompanying drawings forming part of this application in which similar reference characters indicate like parts in the several views in which—

Figure 1 is a plan view of the device. 45 Fig. 2 is a front view of the device certain parts being broken away and other parts being shown in sections. Fig. 3 is a section along the line 3—3 of Fig. 1 looking in the direction of the arrows. Fig. 4 is a section 50 on the line 4—4 of Fig. 5 looking in the direction of the arrows. Fig. 5 is a section along the line 5—5 of Fig. 4 looking in the direction of the arrows. Fig. 6 is a section along the line 6—6 of Fig. 5 looking in the 55 direction of the arrows. Fig. 7 is a perspective view of the clutch mechanism, a

portion of the parts being shown in section. Fig. 8 is a perspective view showing the means for connecting the keys of the master typewriter with the operating parts of the 60 duplicator. Fig. 9 is a section through the paper holder roller, part of the roller being shown in side elevation. Fig. 10 is a perspective view showing the connection between the paper holder rollers of the master typewriter and the duplicator. Fig. 11 is a perspective view of the drive sprocket 65 for the paper holder rollers. Fig. 12 is a perspective view of the means for journaling and locking the shaft of the paper 70 holder rollers. Fig. 13 is a perspective view showing one end of the paper holder and the means for tearing off the paper. Fig. 14 is a section along the line 14—14 of Fig. 3, and Fig. 15 is a perspective view of a 75 modified form of the connecting mechanism between the main typewriter and the duplicator.

This application is a division of a prior application Serial No. 837,185 filed May 8, 80 1914. In said prior application I have embodied claims to the general structure of the duplicating device. The claims in the present application are directed to the paper 85 holders and feeding means of the duplicating device. In order that the action of the paper feeding means may be fully understood I have described the structure and operation of the duplicator in the present application.

90 In carrying out my invention I provide a typewriter of any suitable make. In the drawings I have indicated a typewriter of the so-called basket type, but it will be understood that the same principle of operation 95 might be applied to typewriters of other forms without departing from the spirit of the invention. In Fig. 1 the keyboard of the main or master typewriter is shown at 1, this keyboard being provided 100 with the usual keys 2. Disposed at one side of the master typewriter is a second typewriter. In this second typewriter the keyboard 1^x has no keys. In fact the keyboard itself might be dispensed with as far as the 105 keys themselves are concerned except that downwardly projecting portions thereof form convenient bearings for the rock shafts which operate the type bars. For this reason I prefer to make use of machines 110 which have a keyboard, from which the keys are removed. A third typewriter hav-

ing a keyboard 1^y may also be provided and in fact other typewriters might be added, these additional typewriters being mere duplicates of the one adjacent the master typewriter.

The frames of the master typewriter and the duplicator immediately adjacent are connected securely together as by means of a front plate 3 and a metallic band 4 running rearwardly therefrom between the two typewriters. The upper part of the frames of the master typewriter and the duplicator immediately adjacent is connected by means of a bar such as that shown at 5. In order to further bind the two machines together so that they may form a rigid unitary structure, braces 6 may be secured to the bottoms of the frames of the two machines, these braces being secured to a common base 7, as shown in Fig. 2. Securing devices 3^x, 4^x, 5^x, and 6^x similar to the securing devices 3, 4, 5 and 6 are provided for holding the adjacent duplicators together.

The means for connecting the keys 2 of the master typewriter to the working parts of the duplicators is clearly shown in Fig. 8. In this figure the keys 2 are provided with stems 8 which are pivotally connected at 9 to arms 10 which are rigidly secured to rock shafts 11. Each of these rock shafts 11 is provided with the usual arm 12 which is connected by means of a link 13 with the type bar (not shown) in the usual manner. It will be observed, however, that each of the rock shafts 11 is provided with an L-shaped arm 14 which is connected by means of a link 15 with an arm 16 on the rock shaft 17 of the nearest duplicator. A similar link 18 may extend to the corresponding rock shaft of the next duplicator, so that when a key 2 is pressed on the master typewriter the rock shaft of the master typewriter corresponding to the key and also the rock shaft of the duplicator corresponding to the key will be rocked. The duplicator rock shaft 17 has an arm 12^x which is connected by a link 13^x with a type bar similar to the type bar which is operated by a pressure of the key on the master typewriter. Turn buckles such as that shown at 19 are provided for adjusting the effective lengths of the links 15 and 18. Each key of the master typewriter is connected with the adjacent duplicator in precisely the same manner.

As will be seen from Fig. 6 the shaft 20 of the platen 21 of the master typewriter is extended beyond the bearing 22 and beyond the stop 23 carried by the framework 24 and is provided with a gear wheel 25 which is securely fastened to the shaft by means of a pin 26 or in any other suitable manner. The shaft 20 has a reduced portion 20^a arranged to enter a socket 27^a of the shaft 27 which bears the platen 21^x of the adjacent

duplicator. The shaft 27 bears a gear 28 having a hub 29 loosely mounted on the shaft 27 and provided with a circumferential groove 30 in which a yoke 31 is arranged to extend. This yoke is borne by a lever 32 which is pivotally mounted at 33 (see Fig. 1) on the bar 5 which connects the master typewriter with the adjacent duplicator. The hub 29 has an extension provided with slots 34 arranged to receive guide members 35 formed integrally with the shaft 27. A pin 36 passes through the shaft 20 and the ends of the pin are adapted to enter the slots 34 when the gear 28 is moved toward the gear 25.

Referring now to Fig. 5 it will be seen that the bearing 22 of the master typewriter is provided with an upwardly extending arm 37, the end of which forms a bearing 38 for a shaft 39 disposed parallel with the shafts 20 and 27. The opposite end of the shaft 39 is journaled in a bearing 40 of the duplicator typewriter similar to the bearing 38 of the master typewriter. Loosely mounted on the shaft 39 is a sleeve 41 which bears two gears 42 and 43 respectively and an intermediate sprocket wheel 44. The gear 43 is constantly in mesh with the gear 25. The gear 28 may assume any one of three positions, to wit; that shown in Fig. 5, in which it is in mesh with the gear 42; an intermediate position shown in dotted lines in Fig. 5, in which it is out of mesh with the gear 42, or a position to the right in which the hub 29 is far enough over to cause the pin 36 on the shaft 20 to enter the slot 34. Now the relation of the gears 25, 43, 42 and 28 is such that when the device is in the position shown in Fig. 5 a rotative movement of the platen shaft 20 which bears the gear 25 will cause a rotative movement of the shaft 27 of the duplicator to just half the extent of the angular rotation of the shaft 20. In other words, the gears 25, 43, 42 and 28 are reducing gears. It will therefore be apparent that in line spacing the movement of the platen to form a double space will result in a single space movement of the duplicator when the gears are in the position shown in Fig. 5.

The lever 32 is provided with a locking segment 45 (see Fig. 1) and this lever may assume any one of three positions. When it is thrown over to the right the gears are set as shown in Fig. 5; when it is in intermediate position, then the gear 28 is out of mesh with the gear 42, and when it is thrown over to the left the clutch member 36 enters the slot 34 of the companion clutch member, thereby connecting the two shafts 20 and 27 together so that the duplicator will now space the same as the master typewriter.

Disposed at the rear end of the type-

writer frame is a laterally projecting extension 46 having an upstanding arm 47. The opposite end of the aligned row of typewriters is provided with a similar extension and arm. The upper end of the arm is recessed to provide a retaining socket for a shaft 48 which is held in position by means of a hook 49 (see Fig. 12). Disposed on the shaft is a sleeve 50 which is provided with ball bearings 51 at one end and with ball bearings 52 at the other end. One of the bearing members 52 is extended as shown at 53 to form a sleeve and this sleeve is provided with an annular groove 54. The sleeve 50 is provided at one end with an enlarged portion having a pin 55. A spool 56 is provided with an L-shaped slot 57 at one end (see Fig. 10) and is arranged to fit over the inner sleeve 50 and to be secured to the latter by the bayonet joint formed by the pin 55 in the slot 57. This spool is provided with a longitudinal slot 58 (see Fig. 9).

I have described one of the paper rollers, but it will be seen from Fig. 10 that each machine is provided with two rollers, an upper and a lower roller. The upper rollers are all disposed on the shaft 48 while the lower rollers are disposed on a shaft 59 which is carried by the arms 47 at a level which is substantially that of the upper part of the extension 46 (see Fig. 2). This shaft 59 extends directly from one upright 47 to the other. Between the master typewriter and the adjacent duplicator is an H-shaped frame member 60 which may be secured by means of a laterally extending arm such as that shown at 61 in Fig. 10 to the carriage frame of either the master typewriter or the duplicator or both. The ends of the H-shaped frame member 60 are forked as shown at 60^a to enter the annular grooves such as those shown at 54 and 54^a in Fig. 9, thereby causing a longitudinal movement of the rollers along their respective shafts whenever the carriages are moved.

Disposed loosely on the contiguous ends of the sleeves 53 and 53^a (see Fig. 9) is a sprocket wheel 62 having a central flange 62^a which enters between the contiguous ends of the sleeves 53 and 53^a so as to prevent longitudinal movement of the sprocket wheel on the sleeves, but which does not prevent rotary movement of the sprocket with respect to the sleeves. Springs such as those shown at 63 extend laterally over each side of the sprocket wheel 62 and are bent inwardly so as to maintain a frictional engagement with the sleeves 53 and 53^a. A sprocket chain 64 passes over the teeth of the sprocket wheel 62 and over the sprocket wheel 44 which is disposed intermediate of the gears 43 and 42. It will be apparent that any movement of the sprocket wheel 44 will be communicated to the sprocket wheel

62 and this movement in turn will be imparted to the rollers of both the master typewriter and the adjacent duplicator through the medium of the springs 63.

Secured upon the rear parts of the carriages are curved paper guides like that shown at 65 in Figs. 3 and 13. These guides are provided with cut-away portions 65^a as shown in Fig. 13. Carried by the curved paper guide 65 on the master typewriter are arms 66 (see Figs. 3 and 13) which support a plate 67. This plate forms a support for the typewritten matter as it comes from the platen. In order to guide it in position I provide an auxiliary plate or

70 grip of metal 68 near the bottom of the plate 67 the lower ends of the plates 67 and 68 being bent in opposite directions, as shown at 67^a and 68^a to form guide members into which the edge of the paper may be placed as it comes from the platen.

The upper edge 68^a of the plate 68 constitutes a knife edge or cutting edge along which the paper may be torn or cut off. At one edge of the plate 67 is a scale 69 (see Fig. 2) which is provided with perforations 70. Slidable on this scale is a laterally extending stop arm 71 which bears a spring actuated plunger 72 having a thumb piece 73. The thumb piece 73 may be raised so as to permit the arm 71 to be adjusted in various positions along the scale, and when released will cause the plunger 72 to enter one of the openings 70 so as to lock the stop arm 71 in adjusted positions.

From the foregoing description of the various parts of the device the operations thereof may be readily understood.

The spools 56 (see Fig. 9) are designed to be supplied with paper wound therein in a roll of unbroken length. The spool containing the roll is placed on the lower shaft by removing the latter from its bearings and slipping the spools over their respective sleeves such as that shown at 50 in Fig. 9, and locking them in position by means of the bayonet joint, as described. It will be understood that the paper supply rolls are placed in position for the master typewriter as well as for the duplicators. The paper is then passed over the curved guides 65 underneath the platens of the respective typewriters and the edge of the paper on the master typewriter is passed into the guide slot between the edges 67^a and 68^a of the plates 67 and 68 (see Fig. 13). The stop arm 71 is now moved into position on the plates 67 so as to indicate the proper length of the various sheets. The carriages of the master typewriter and the duplicators being rigidly connected together, move in unison and they are set in position for writing simultaneously with the position of the carriage of the master typewriter. If it is desired to have the original sheet, i. e., the

one on the master typewriter written with double space lines and the copies written with single space on the duplicators the lever 32 is shifted into the position shown in Fig. 1.

Now on operating the master typewriter in the usual manner the duplicators will make duplicate copies of the original with the exception that these copies will be single spaced instead of double spaced, as explained. It will be observed that as the carriages of the machines travel forward they will carry with them the paper rolls so that the platens of the typewriters and the paper rolls maintain their same relative positions.

The lever 74 (see Fig. 2) is the ordinary lever by means of which the platen of the master typewriter is rotated for line spacing and by which the carriages of the typewriting machines are moved when the end of a line is reached. It has been previously explained how the revolution of the shaft 20 of the master typewriter will cause the revolution of the shaft of the duplicator adjustment 25 cent to it one half the angular revolution of the shaft 20. If more than one duplicator is used the shafts of the platens of the duplicators are rigidly connected together.

When the upper end of the sheet reaches the stop arm the operator grasps the sheet and tears it off on the knife edge or tearing edge 68^b. The sheets which are thus torn off are precisely of the same length.

The movement of the sprocket wheel 44 causes the revolution of the sprocket wheel 62 through the medium of the chain 64, as heretofore described, and this causes the revolution of the upper paper rollers. The duplicate records which are being made on the platens of the duplicators are passed over the paper guides 65 and the ends of the paper are cut and are inserted in the slots 58 of empty spools. The revolution of the spools by the frictional engagement of the springs 63 with the sleeves 53, 53^x etc., causes the paper to be rolled up as fast as it is fed forwardly by the line spacing mechanism. Thus while sheets of uniform size are being torn off from the master typewriter a continuous sheet containing duplicate copies of the letters or other matter written on the separate sheets is wound on the upper rolls of the duplicators.

Instead of tearing off the sheets from the supporting means on the master typewriter the sheets may be passed directly from the platen over the guide 65 (see Fig. 13) and may be wound on a paper holder or spool carried by the upper rod 48 so that the matter written on the master typewriter may be kept on a roll of continuous length if desired.

In Fig. 15 I have shown a modified form of means for transmitting the movement of a key of the master typewriter to that of

the duplicators. In this form the key 2^k of the master typewriter is at the end of a laterally extending arm 11^k. The arm bears on a roller 9^k on an arm 10^k secured to a rock shaft 15^k. This rock shaft extends past the mechanism of the duplicator and is provided with an arm 16^k having a roller 17^k arranged to engage a lever 18^k which operates a key of the duplicator corresponding to the key 2^k of the master typewriter. The other keys are connected in the same manner.

It will be seen that I have provided a device in which duplicate copies of the original may be made either having the same line spacing or line spacing one half that of the originals. Moreover these duplicate copies have the advantage of being as plainly legible as the original, since they are, in a sense, original copies themselves. Most carbon copies are not as plain as the original. The provision of means whereby the duplicate copies may be rolled on paper rolls obviates the necessity of removing the duplicate and filing them away as they would have to be were carbon copies prepared. The whole record may be lifted out from the duplicators when the roll is filled up and may be filed with very little trouble. The device is positive in its action so that no matter what is written on the master typewriter a true record is made on the duplicators.

If it is desired to use the master typewriter by itself the lever 32 need only be shifted to the neutral position, *i. e.*, the central position. This disconnects the line spacing mechanism of the duplicators from that of the master typewriter. It also disconnects the driving mechanism of the upper paper rolls of the duplicators. If for any reason it is desirable to turn the upper paper roller of either the master typewriter or the duplicators relatively to one another, this may be accomplished since the rollers are held only frictionally by the springs 63. When, however, it is desired to have the rollers turned in unison the springs 63 are sufficiently strong to cause the revolution of the rollers as the sprocket 62 is rotated.

This device is primarily designed to be used in connection with an electrical or other power device for operating the keys. Such devices are common and the application of the same to the keyboard of the master typewriter is well understood. I have found in practice that a single duplicator may be very easily operated by the manual manipulation of the master typewriter in the ordinary manner.

I claim:

1. The combination of a master typewriter and a duplicating typewriter controlled thereby, of extensions on the frames of said typewriters, a pair of parallel rods carried by said extensions, an upper and a lower paper roller for each machine, said

upper rollers being disposed on one of said rods and said lower rollers being disposed on the other rod, all of said rollers being 5 slideable longitudinally of their respective rods, and means secured to the carriage of one of said typewriters and arranged to engage 65 said rollers for causing a longitudinal movement of the rollers along their shafts when the carriage is moved, said means permitting the revolution of the rollers on their respective shafts, means for revolving the 70 upper rollers, said last named means comprising a sprocket wheel rotatably mounted on portions of contiguous rollers, said sprocket wheel having spring arms arranged to frictionally engage said portions 75 of the rollers, a sprocket wheel rotatably carried by the carriage of said master typewriter, connections between the two sprocket wheels, and means actuated by the line spacing mechanism of the master 80 typewriter for rotating said last named wheel.

2. The combination with a master typewriter and a duplicating typewriter controlled thereby, of extensions on the frame 15 of said typewriters, a pair of parallel rods carried by said extensions, an upper and a lower paper roller for each machine, said upper rollers being disposed on one of said rods and said lower rollers being disposed 20 on the other rod, all of said rollers being slideable longitudinally of their respective rods, means secured to the carriage of one of said typewriters and arranged to engage 25 said rollers for causing a longitudinal movement of the rollers along their shafts when the carriage is moved, said means permitting the revolution of the rollers on their respective shafts, and means for revolving the upper rollers.

3. The combination of a master typewriter and a duplicating typewriter controlled thereby, of extensions on the frames of said typewriters, a pair of parallel rods carried by said extensions, an upper and a lower paper roller for each machine, said upper rollers being disposed on one of said rods and said lower rollers being disposed 35 on the other rod, all of said rollers being slideable longitudinally of their respective rods, means secured to the carriage of one of said typewriters and arranged to engage 40 said rollers for causing a longitudinal movement of the rollers along their shafts when the carriage is moved, said means permitting the revolution of the rollers on their respective shafts, means for revolving 45 the upper rollers, said last named means comprising a sprocket wheel rotatably mounted on portions of contiguous rollers, 50 said sprocket wheel having spring arms arranged to frictionally engage said portions of the rollers, and means for rotating the sprocket wheel.

4. The combination of a master typewriter and a duplicating typewriter controlled thereby, of extensions on the frame 55 of said typewriters, a pair of parallel rods carried by said extensions, an upper and a lower paper roller for each machine, said upper rollers being disposed on one of said 60

rods and said lower rollers being disposed on the other rod, all of said rollers being slideable longitudinally of their respective rods, means secured to the carriage of one of said typewriters and arranged to engage 65 said rollers for causing a longitudinal movement of the rollers along their shafts when the carriage is moved, said means permitting the revolution of the rollers on their respective shafts, means for revolving the 70 upper rollers, said last named means comprising a sprocket wheel rotatably mounted on portions of contiguous rollers, said sprocket wheel having spring arms arranged to frictionally engage said portions 75 of the rollers, a sprocket wheel rotatably carried by the carriage of said master typewriter, connections between the two sprocket wheels, and means actuated by the line spacing mechanism of the master 80 typewriter for rotating said last named wheel.

5. The combination of a master typewriter and a duplicating typewriter controlled thereby, of extensions on the frame 85 of said typewriter, a pair of parallel rods carried by said extensions, an upper and a lower roller for each machine, said upper rollers being disposed on one of said rods and each of said upper rollers being provided with a sleeve, the ends of the sleeves of the two upper rollers being contiguous, a sprocket wheel of annular form spanning the contiguous ends of the rollers, and means for frictionally securing said 95 sprocket wheel to said sleeves.

6. The combination with a typewriter carriage, of an arm secured thereto and having a yoke at its ends, a rod secured to the main frame of the typewriter, a sleeve rotatably 100 mounted on the rod and slideable therealong, said sleeve having an extension provided with an annular groove arranged to receive the forked end of the arm whereby rotation of the sleeve is permitted and the longitudinal movement of the sleeve along the rod with the typewriter carriage is secured, said sleeve consisting of a cylindrical body portion and having enlarged cylindrical end portions, a hollow cylindrical spool arranged to fit over said sleeve and to bear on said enlarged end portions, said hollow spool being provided with an L-shaped slot, and one of said enlarged end portions being provided with a pin arranged to enter 110 the slot for locking the spools to the sleeve.

HARVEY W. MORLEY.
